(57) **CLAIM**

The ornamental design for a firearm stock, as shown and described.

DESCRIPTION

FIG. 1 is a front, top, right side perspective view of a firearm stock according to the present disclosure.

FIG. 2 is a front, bottom, left side perspective view of the firearm stock of FIG. 1.

FIG. 3 is a rear, bottom, left side perspective view of the firearm stock of FIG. 1.

FIG. 4 is a left side view of the firearm stock of FIG. 1.

FIG. 5 is a right side view of the firearm stock of FIG. 1.

FIG. 6 is a top view of the firearm stock of FIG. 1.

FIG. 7 is a bottom view of the firearm stock of FIG. 1.

FIG. 8 is a front view of the firearm stock of FIG. 1; and, FIG. 9 is a rear view of the firearm stock of FIG. 1.

The broken lines in the figures illustrate portions of the article that form no part of the claimed design. The surface shading in the figures represents contour and not surface ornamentation. The firearm stock includes symbolic breaks along its length drawn in broken lines. The broken break lines and the area between the break lines form no part of the claimed design.
